UNITED STATES PATENT OFFICE.

ANTHONY KEOGH, OF SPRINGFIELD, OHIO, ASSIGNOR TO THE CHANEY MANUFACTURING COMPANY, OF SPRINGFIELD, OHIO, A CORPORATION OF OHIO.

DESIGN FOR A THERMOMETER.

61,414.

Specification for Design.

Patented Aug. 29, 1922.

Application filed January 10, 1922. Serial No. 153. Term of patent 14 years.

To all whom it may concern:

Be it known that I, ANTHONY KEOGH, a citizen of the United States of America, residing at Springfield, county of Clarke, State of Ohio, have invented a new, original, and ornamental Design for a Thermometer, of which the following is a specification, reference being had to the accompanying drawing, forming a part thereof.

In the drawings, the figure is a perspective view showing my new design.

I claim:—

The ornamental design for a thermometer as shown.

In testimony whereof, I have hereunto set my hand this 27th day of December A. D. 1921.

ANTHONY KEOGH.
